UNITED STATES PATENT OFFICE.

GEORGE J. ZISCH, OF NEWARK, NEW JERSEY.

REFRIGERATING-MACHINE.

1,282,516.

Specification of Letters Patent. Patented Oct. 22, 1918.

Application filed January 10, 1918. Serial No. 211,146.

To all whom it may concern:

Be it known that I, GEORGE J. ZISCH, a subject of the Emperor of Germany, residing at Newark, in the county of Essex and State of New Jersey, have invented certain new and useful Improvements in Refrigerating-Machines, of which the following is a specification.

This invention relates to a refrigerating machine which is adapted to produce a low temperature in the refrigerating element in the well known manner of compressing a chemical which is condensed and then volatilized in the refrigerating element from which it is drawn and again conducted to the compressing mechanism.

The invention is a machine of this type which is constructed to be used in a small space so that it does not take up much room, and one in which the different parts are closely assembled whereby the machine can be used for refrigeration in stores and homes replacing the usual ice chamber of ice-boxes with its refrigerating element.

The invention is a machine of this type which is provided with a chamber and suitable pumps inside of the chamber, all the pumps communicating with the chamber, the chamber being provided on its outside with a condensing tank in which the condensing coil is placed. A suitable motor can be mounted on the frame for operating the pumps of the machine, and the whole device is one in which the cooling of the motors is aided by the surrounding of the chamber with the condensing tank.

This application discloses the identical subject-matter shown in my application Serial Number 759,641, filed April 8, 1913.

The invention is illustrated in the accompanying drawing, in which Figure 1 is a section on line 1, 1, in Fig. 2. Fig. 2 is a section on line 2, 2, in Fig. 1. Fig. 3 is a cross section of the suction pump used in the chamber.

The machine consists of a base 10 and the top 11, the top being preferably provided with a suitable lid 12 which can be securely fastened in place and kept air tight when the machine is operating. Between the top and the bottom extend the walls 13 which, with the top and bottom, inclose a chamber 14. Mounted in the chamber are the compression pumps 15 and a suction pump 16. In the compression pumps are mounted the pistons 17 which are operated from the

cranks 18 of the shaft 19, and the shaft 19 being provided with a gear 20 which in turn is operated from the gear 21 on the driving-shaft 22, the driving-shaft 22 having a 60 crank 23 which operates the piston 24 which is to be hereinafter described. The driving-shaft 22 extends beyond the chamber and is provided with a gear 25 which is driven from the gear 26 on a shaft 27, the gear 65 being rotated by means of a worm-gear 28 in mesh with the worm 29 on the shaft 30 of the motor 31. The motor is mounted on the top 11 in the preferred form, although other dispositions of the motor can be made, 70 as will be understood. It will also be evident that different methods of driving the pumps and the motor can be used.

In operating the machine a suitable chemical, such as ammonia, ethyl chlorid or a 75 similar well known chemical, is used and is forced by the pumps 15 from the chamber 14. A gaseous refrigerating agent passes through the openings 32 and is forced to open the check-valve 33, each of the compression pumps being provided with the same equipment of valve, the gas, after it passes the valve, entering the small chamber 34 in the casing 35, the casings of the two compression pumps being joined by a 80 pipe 36 so that the compressed refrigerating agent can pass from the small chambers to a pipe 37 which extends up as at 38 and is formed into a condensing coil 39. The condensing coil 39 is in a tank formed by the 85 wall 13 and a wall 40 which extends around the wall 13 at a distance therefrom. The tank is filled with a suitable cooling liquid, such as water, which enters through the pipe 41 and is drawn off through a suitable outlet pipe 42. A faucet 43 controls the admission of water. The condensing coil emerges from the tank as at 44 and is provided with a suitable valve 45 which permits it to pass after it is condensed so that it is volatilized 90 into a suitable refrigerating element 47. I show a straight pipe in the drawing, but it will be understood that this refrigerating element can be a coil or a tank or any other suitable device in which the expanded chemical produces a very low temperature which in turn is transmitted to the article to be cooled or frozen. The end 48 of the refrigerating element is connected, as in Fig. 3, to the bottom 10 of the machine by means of a box 110

49 which contains a suitable check-valve 50,

The check-valve 51 is mounted in the piston 24, the piston 24 reciprocating in the suction pump 16, the suction pump thus drawing the volatilized or gaseous chemical from the refrigerating element 47 and forcing it back into the chamber 14.

The gears 21 and 20 are proportioned so that the suction pump will compensate for the compression pumps. In other words, as 10 in the drawing, the gears are proportioned two to one in size, whereby the single suction pump makes two strokes to one stroke of each of the compression pumps. This maintains the same pressure in the chamber 15 so that the material, when it is pumped by the compression pumps, is in condition to be condensed in the coil 39.

It will be noticed that there is a great economy in space on account of the wall 13 20 acting as the outer wall of the chamber and also the inner wall of the tank, the condensing tank having a cooling influence on the chamber and its working parts within.

This machine takes up very little room 25 and is particularly adapted for use in houses and stores, is easily manipulated, and when once it is set in motion it is somewhat automatic in its operation and maintains a steady low temperature. It is also economical in 30 its use of chemicals, since the chemical employed has but small path of travel, the chamber and the compression and suction pumps being grouped in a manner to make the passage of the chemical short between its 35 exit from the freezing element and its entrance into the condensing coil.

Having thus described my invention, what I claim is:

1. A refrigerating machine comprising a 40 chamber, a compression pump in the chamber, a suction pump in the chamber, a condensing tank surrounding the chamber, a condensing coil in the tank, a connection from the condensing coil to the compression pump, a refrigerating element, a connection from the refrigerating element to the coil, a connection from the refrigerating element to the suction pump, and means for operating the pumps.

50 2. A refrigerating machine comprising a chamber, compressing pumps in the chamber, a suction pump in the chamber, a condensing tank surrounding the chamber, a

condensing coil in the tank, a connection from the condensing coil to the compression pumps, a refrigerating element, a connection from the refrigerating element to the coil, a connection from the refrigerating element to the suction pump, a connection between the pumps for operating them in 55 their proper cadence, and means extending to the exterior of the chamber for operating the pumps.

3. A refrigerating machine comprising an inclosed chamber, an inclosed tank surrounding the chamber, compression pumps in the chamber and in communication therewith, a suction pump in the chamber and in communication therewith, a coil in the tank and surrounding the chamber, a connection 60 from the coil to the compression pumps, a refrigerating element connected at one end to the coil, and a connection from the refrigerating element to the suction pump.

4. A refrigerating machine comprising a 75 chamber, compression pumps in the chamber, a suction pump in the chamber geared with the compression pumps, a condensing tank surrounding the chamber, a condensing coil in the tank, a pipe for connecting the 80 condensing coil and compression pumps, a refrigerating element, a pipe for connecting the refrigerating element and said coil, a pipe for connecting the refrigerating element and suction pump, and a motor connected to one of the gears for operating the 85 pumps.

5. A refrigerating machine comprising a chamber, compression pumps in the chamber, a suction pump in the chamber arranged 90 between the compression pumps and being geared to said compression pumps, a condensing tank surrounding the chamber, a condensing coil in the tank, a refrigerating element, said pumps, condensing coil and 95 refrigerating element having communication with respect to each other and means for operating the pumps.

In testimony, that I claim the foregoing, I have hereunto set my hand this 29th day of December 1917.

GEORGE J. ZISCH.
